UNITED STATES PATENT OFFICE

KARL KAMMÜLLER, OF FRANKFORT-ON-THE-MAIN, GERMANY

CHAMBER WATER LOCK

Application filed September 19, 1929, Serial No. 393,815, and in Germany June 7, 1929.

Upon sudden increases in demand, the lower chamber of a water lock is required to supply from its contents the increased requirement for water by the works, until the 5 sturm supply, which only gradually accommodates itself to this increased demand, has attained the required speed. The quicker the sturm supply is accelerated, the smaller will be the necessary capacity of the chamber. The deeper the lower chamber, the greater will be the acceleration. Also in 10 order to save space the lower chamber, is disposed as low as is practically possible.

The deepest position hitherto employed 15 has been a certain safety height above the outgoing sturm, in order to avoid the entry of air therein.

The present invention is an improvement 20 on the water chamber for which Letters Patent of the United States No. 1,705,089 were granted to me March 12, 1929 and consists essentially in a simple arrangement for disposing the chamber below the usual height, 25 approximately at the level of the outgoing sturm or even lower and preventing the entry of air into the sturm, in that the chamber is divided from the sturm by a wall under which the water can flow. The invention is illustrated in Figs. 1 to 3 of the accompanying 30 drawings.

Figure 1 represents a vertical section 35 through a water lock. S indicates the shaft, A the upper chamber, and B the lower chamber. The latter is arranged at the level of the sturm R and is separated therefrom by the suspended sill or wall T which is advantageously indicated as an underflow weir. The channel V below this wall T connects the shaft A or chamber B with the sturm.

Figure 2 shows a horizontal section 40 through the chamber and sturm.

In Figure 3 a modified construction is illustrated. Instead of a concrete wall being employed, the seal between the chamber and the sturm is formed by a portion of rock t which is left in place and through which a channel v is driven. The highest point of the channel v must naturally lie at a lower depth than the bottom of chamber B.

In the sturm itself there exists a certain

low pressure which is given by the lowest level in the chamber. The lowest possible position of the lower chamber is determined by the practically permissible value of the pressure in the sturm.

The economy of space that may be obtained depends upon the hydraulic data of the sturm and naturally varies from case to case. Generally it is very substantial, and in the most favourable cases the necessary capacity 55 of the chamber is reduced to a fraction.

The operation is substantially the same as described in the before mentioned Letters Patent. During normal operation the water in the shaft S is at a height equal to that of the water in the reservoir from which the water flows. If the load varies, the velocity 60 of the water in the gallery cannot suddenly adapt itself to the changed demand; the water chamber B then acts as an elastic member, taking up excess of water from the gallery when the load decreases, and letting water pass into the gallery when the load increases, until the velocity of water passing 65 through the gallery has adapted itself to the new load.

Now, if while the chamber is filled, there should occur a sudden increase in the load, because of the greater demand, the water level in the shaft S will drop quickly to the 70 chamber B and the demand for water will be supplied quickly to the sturm from the water in the compartment B.

I claim:

In a water chamber of the type described, 75 a head shaft, an upper chamber, a sturm, a lower chamber in open communication with the lower end of the head shaft, and arranged at substantially the level of the sturm, and a downwardly extending sill dividing the 80 lower end of the shaft from the sturm so that the lower chamber is at normal pressure and the shaft is at negative pressure.

In testimony whereof I have hereunto set my hand this 3d day of September, A. D. 95 1929.

KARL KAMMÜLLER.
